UNITED STATES PATENT OFFICE.

FREDERICK A. WIELAND, OF CHICAGO, ILLINOIS.

SPEEDOMETER.

1,137,822.

Specification of Letters Patent.

Patented May 4, 1915.

Application filed January 13, 1914. Serial No. 811,831.

To all whom it may concern:

Be it known that I, FREDERICK A. WIELAND, a citizen of the United States, and a resident of the city of Chicago, county of Cook, and State of Illinois, have invented certain new and useful Improvements in Speedometers, of which the following is a specification.

My invention relates to improvements in self-propelled vehicles and has for its object the provision of means for preventing the over-speeding of vehicles.

The invention consists in the combinations and arrangements of parts hereinafter described and claimed.

The invention will be best understood by reference to the accompanying drawings, forming a part of this specification, and in which—

20 Figure 1 is a side view of an automobile equipped with means embodying my invention, Fig. 2, an enlarged end view of the same, Fig. 3, an enlarged horizontal section taken through a signal casing arranged at 25 the rear of the automobile, Fig. 4, a section taken on line $x-x$ of Fig. 3, Fig. 5, an enlarged horizontal section taken through a sign drum employed in the construction, Fig. 6, a section taken on line $y-y$ of Fig. 30 3, Fig. 7, an enlarged detail view showing the registering mechanism employed in the construction, Fig. 8, a different view of said registering mechanism, and Fig. 9, a diagrammatic view illustrating the electric 35 circuits employed in the construction.

The preferred form of construction as illustrated in the drawings comprises a signal casing 1 which is secured to the rear of the body of the automobile 2 at one side 40 thereof, as shown. A hollow sign drum is arranged in said casing, said drum being provided with a plurality of translucent sign plates 3 preferably made of glass and having numbers placed thereon to indicate 45 the permissible speeds of travel of an automobile in different localities. This drum is provided with bearings 4 at each end thereof which in turn are rotatably mounted on a hollow shaft 5 suitably supported in casing 50 1. At its outer end said drum carries a knurled operating wheel or handle 6 which is provided with notches 7 coöperating with a spring detent 8 to hold said drum yieldingly in its different operative positions with the different sign plates 3 registering 55 with a sight opening 1' in the side of casing 1 and covered by a plate of glass or other transparent material, as indicated. Arranged opposite wheel 6 is a swinging door 9 which is adapted to give access to the 60 interior of casing 1 and permit the setting of the sign drum in any of its operative positions, said door being provided with a suitable lock 10 for closing the same.

Arranged on the inner end of the sign 65 drum is an electric contact ring 11 which is provided with radiating fingers 12, 13, 14, 15, 16 and 17 of different radial lengths, said ring serving as a means for placing said fingers in constant electrical communication with a spring electric contact finger 18, as will be readily understood. The finger 18 is connected by means of a wire 19 with the negative side of a battery 20, the positive side of said battery being connected 70 by means of a wire 21 with one side of an electric signal bell 22. The other side of bell 22 is connected by means of a wire 23 with a sleeve 24 which is slidably mounted on a rod 25 positioned radially and adjacent 75 the contact member 11. Sleeve 24 carries a contact finger 26 arranged to contact with the different fingers 12, 13, 14, 15, 16 and 17 when said sleeve 24 is moved inwardly and radially with reference to the sign 80 drum. Sleeve 24 also carries an operating arm 27 which is in operative connection with a sleeve 28 slidable on governor shaft 29 arranged in casing 1, as shown. Sleeve 28 is connected by means of links with governor 90 balls 30 carried by swinging arms 31 pivotally connected with a head 32 rigidly fastened to governor shaft 29. Governor shaft 29 is connected with a shaft 33 which extends forwardly under the body of the automobile and is connected at its forward end by means of a flexible shaft 34 with a pinion 35 meshing with a gear 36 on one of the front wheels of the automobile, as shown in Fig. 1. By this arrangement, it will be observed that upon increase of speed of the automobile, the contact 26 will be drawn

inwardly and radially with reference to the sign drum by the action of the centrifugal governor on governor shaft 29, as indicated in dotted lines in Fig. 3, and that the faster 5 the speed of travel of the automobile, the further the contact 26 will be drawn inwardly with reference to said drum. As will be observed the contact fingers 12, 13, 14, 15, 16 and 17 are of different radial 10 lengths so as to make contact with contact 26 at different radial positions thereof. Fingers 12, 13, 14, 15, 16 and 17 are so arranged with reference to the sign plates 3 that the shortest finger 11 corresponds with 15 the sign plate indicating the highest permissible speed and so on so that when a sign plate is arranged opposite sight opening 1' the corresponding finger which has a radial length to correspond with said sign 20 plate is set in operative relation with contact 26. The arrangement is such that, when the speed of the vehicle reaches or exceeds the speed limit indicated by the corresponding sign plate, electrical contact will be made 25 between the contact 26 and the corresponding finger.

An electric switch 37 has its pivotal end connected by a wire 38 with one side of a plain or white electric light bulb 39 which is fixed to tube 5 within the sign drum, as indicated. The free end of switch 37 is normally held in contact with electric contact 40 by means of a spring 41, said contact 40 being connected by means of a wire 40' with 30 wire 21 and thus with the positive side of battery 20. The other side of light 39 is connected by means of a wire 42 with the minus side of battery 20, as indicated in Fig. 9. By this arrangement it will be observed 35 that the white electric light 39 will be normally maintained in an excited or lighted condition thus exhibiting one of the sign plates 3 through sight opening 1' at night, said sign being arranged to be clearly visible in the day time without the light.

An electrical magnet 43 is connected in parallel with the electric bell 22 and in operative relation with switch 37 so that when electrical contact is made between contact 26 50 and any one of the contact fingers 12, 13, 14, 15, 16 or 17, a circuit is also formed through said electro-magnet, the arrangement being such that excitation of magnet 43 withdraws switch 37 from operative connection with 55 contact 40, thus breaking the circuit through light 39. This simultaneously establishes a circuit through a red or other distinctly colored light 45 which is connected in circuit by means of wires 44 and 46 and changes the 60 character of the visual signal so as to exhibit a red light thus indicating that the automobile is exceeding the speed limit indicated by the sign plate 3 in position and at the same time ringing the bell 22 as explained above.

Thus officers and other observers will be 65 forcibly notified both audibly and visually that the automobile is being driven at a speed above the indicated speed limit therefor.

Switch lever 37 is connected by means of a 70 link 47 with the operating arm 48 of an ordinary registering device 49 which is set in casing 1 opposite sight opening 50, the arrangement being such that at each operation of lever 37 register 49 will be operated 75 to register the same. By this arrangement, it will be observed that an accurate register will be kept of each time the speed limit has been exceeded, thus enabling the owner to determine whether or not his car is being 80 carelessly driven.

While I have illustrated and described the preferred form of construction for carrying my invention into effect, this is capable of variation and modification without departing 85 from the spirit of the invention. I, therefore, do not wish to be limited to the precise details of construction set forth, but desire to avail myself of such variations and modifications as come within the scope of 90 the appended claims.

Having described my invention what I claim as new and desire to secure by Letters Patent is:

1. The combination with a self-propelled 95 vehicle, of a casing carried thereby and provided with means for viewing the interior at one side thereof; a rotatable drum mounted in said casing opposite said viewing means; translucent speed signs on the sides 100 of said drum; different colored electric lights in said drum; means operable by the speed of said vehicle for controlling said lights; and a signal operable by said means, substantially as described.

2. The combination with a self-propelled vehicle, of a casing carried thereby and provided with means for viewing the interior at one side thereof; a rotatable drum mounted in said casing opposite said viewing 110 means; translucent speed signs on the sides of said drum; different colored electric lights in said drum; and means operable by the speed of said vehicle for controlling said lights, substantially as described.

3. The combination with a self-propelled vehicle, of a casing carried thereby and provided with means for viewing the interior at one side thereof; a rotatable drum mounted in said casing opposite said viewing means; translucent speed signs on the sides of said drum; different colored electric lights in said drum; separate circuits for said lights; electric contacts at different radial positions on said drum; a radially slid able electric 125 contact co-operating with said contacts; centrifugal means operable by the speed of the vehicle and connected to operate said radi-

ally slidable contact; an electro-magnet; circuits for said electro-magnet controlled by said contacts; and a switch operable by said magnet and arranged to open one of said 5 light circuits and close the other light circuit, substantially as described.

In testimony whereof I have signed my

name to this specification in the presence of two subscribing witnesses.

FREDERICK A. WIELAND.
